UNITED STATES PATENT OFFICE.

AUGUST BORNEMAN, OF LANCASTER, OHIO.

IMPROVEMENT IN CORN-SHELLER CASES.

Specification forming part of Letters Patent No. 135,029, dated January 21, 1873.

To all whom it may concern:

Be it known that I, AUGUST BORNEMAN, of Lancaster, county of Fairfield, State of Ohio, have invented a new and useful Improvement in Corn-SHELLERS, of which the following is a full, clear, and exact description, reference being had to the accompanying drawing making part of this specification, in which—

Figure 1 is a perspective view of my improved sheller with the bonnet removed. Fig. 2 is a detached view of the bonnet. Fig. 3 is a detached view of the same in an inverted position; and Fig. 4 is the gear-stand on which the crank and driving-gear are mounted.

Similar letters of reference denote corresponding parts in all the figures.

The invention relates to a new construction of the casing of the sheller; and consists in making said case in two parts, one of which is wood and the other metal, the metal portion having, by preference, the upper part of the cob-carrier or chute attached to it, whereby certain advantages are attained, as will hereinafter be set forth.

In the drawing, A A' are the posts, B B¹ B² the sides, and C the top, of the inclosing-case. D is the picker-wheel. The inner face of this wheel extends some distance beyond the outer line or edge of the cogs, thus forming a flange of such diameter as to lap over and protect the spaces between the cogs of the pinion with which wheel D engages and effectually prevent the corn from getting between these gears. E is a spur-gear mounted on the shaft d' of picker-wheel D. F is a driving spur-gear mounted upon a stud or silent axle projecting from a gear-stand, f, and meshing with gear E. F' is the crank. The eye of the crank is, by preference, circular in form, and is mounted on the hub of gear E, to which it is secured by a bolt, f'. I prefer this method of applying the crank instead of making the hub of gear F square and then casting the eye of the crank to fit it, as the parts are much less liable to breakage. It will be readily seen that by this arrangement of the crank and the gears E F the operator can stand up on the right-hand side of the sheller to operate it, as the picker-wheel is driven in a reverse direction from the crank. The balance-wheel H is mounted upon the shaft of the

fluted wheel which is employed in this class of shellers, and is driven by the picker-wheel D. One end of the shaft of wheel H is supported in a bearing cast for it on the gear-stand f. G is the throat through which the corn is fed. The usual rag-piece or tongue is attached to the inside of this throat, and is adjusted by means of a set-screw, g. The rear end of the rear upper panel of the case conforms substantially to the outline of wheel D, as shown at B², the front upper panel B and top C being cut off at about a right angle on a line at or near the center of said wheel D. I I¹ is a bonnet, which serves to complete the inclosing-case, the vertical wall I being rounded to correspond with the opposite side at B², the other portion I¹ forming an extension of the top C. This bonnet is provided with an opening, K, through which the cobs are delivered. I² is the cob-carrier, made in substantially the same shape as in ordinary side-delivery shellers, and bolted to the framework. I² is a wing-piece, cast in one piece with the bonnet, and forming the upper part of the cob-chute. The position of the bonnet and chute is shown in dotted lines in Fig. 1. i i are flanges on the bonnet, by means of which it may be secured to the wooden portion of the case.

From the above description it will be seen that full and free access can be had to the interior of the sheller by merely removing the bonnet without disturbing the feeding-throat; and I regard the arrangement of the cob-chute at the corner of the case as being a very desirable one.

As the wing I² can be cast in one piece with the bonnet, the construction is cheapened, the time which is required to apply a separate piece being saved.

The employment of the two gears E and F, thus driving the picker-wheel D in an opposite direction from the rotation of the crank, enables the operator to stand on the right-hand side of the sheller and turn it with his right hand while he feeds it with his left; and, as these gears are mounted wholly outside of the casing, they are not liable to be obstructed, and are easily applied and replaced when broken or worn out.

The front posts A extend the full height of

the sheller; but, in consequence of using the bonnet to complete the rear part, I am enabled to make the rear posts short, and to extend the girts *a* beyond said posts and make handles of them, as at *a'*, which are very convenient in handling the sheller.

Having now described my invention, what I claim as new, and desire to secure by Letters Patent, is—

The herein-described shell or casing for a

corn-sheller, consisting of the wooden portion B B¹ B² C and the metallic bonnet I I¹, substantially as described.

In testimony whereof I have hereunto set my hand this 13th day of September, A. D. 1872.

AUGUST BORNEMAN.
